Patented Dec. 28, 1965

203,375

ROTARY HYPODERMIC SYRINGE

Rosario Russo, 4115 N. Delay Ave., Covina, Calif.

Filed Feb. 8, 1965, Ser. No. 83,713

Term of patent 14 years

(Cl. D83—12)

Fig. 1

Fig. 5

Fig. 2

Fig. 3

Fig. 4

FIGURE 1 is a top view of my new and original design for a rotary hypodermic syringe;

FIGURE 2 is an end elevation viewing it from the right to the left of FIGURE 1;

FIGURE 3 is an end elevation viewing it from the left to the right of FIGURE 1;

FIGURE 4 is a side elevation of FIGURE 1; and

FIGURE 5 is a bottom view of FIGURE 4 with needle protector removed.

I claim:

The ornamental design for a rotary hypodermic syringe, as shown.
